UNITED STATES PATENT OFFICE.

LEWIS M. BARKHURST, OF AKRON, OHIO.

DESIGN FOR A TIRE.

44,510.

Specification for Design.

Patented Aug. 19, 1913.

Application filed June 5, 1913. Serial No. 772,005. Term of patent 7 years.

To all whom it may concern:

Be it known that I, LEWIS M. BARKHURST, a citizen of the United States, and a resident of Akron, Summit county, Ohio, have invented a certain new, original, and ornamental Design for Tires, of which the following is a specification, reference being had to the accompanying drawing, forming part hereof.

The drawing presented is a perspective view of a tire showing my new design.

I claim:

The ornamental design for a tire, as shown.

LEWIS M. BARKHURST.
